UNITED STATES PATENT OFFICE.

JOSEPH HOVEY, OF FLORIDA, OHIO.

SWINGING STRAW-STACKER.

SPECIFICATION forming part of Letters Patent No. 420,301, dated January 28, 1890.

Application filed May 20, 1889. Serial No. 311,365. (No model.)

To all whom it may concern:

Be it known that I, JOSEPH HOVEY, a citizen of the United States, and a resident of Florida, in the county of Henry and State of Ohio, have 5 invented certain new and useful Improvements in Swinging Straw-Stackers; and I do declare the following to be a full, clear, and exact description of the invention, such as will enable others skilled in the art to which it applies 10 to make and use the same, reference being had to the accompanying drawings, and to letters of reference marked thereon, which form a part of this specification.

Figure 1 of the drawings is a side elevation 15 of the machine. Fig. 2 is a top plan view. Fig. 3 is an end view. Fig. 4 is a vertical section on the line X X of Fig. 1. Fig. 5 is a sectional detail. Fig. 6 is an enlarged detail perspective view showing more particularly the 20 turn-table and adjunctive parts. Fig. 7 is an enlarged detail sectional view thereof.

In the embodiment of my invention I employ a base-frame A, of suitable construction, which is bolted at its inner lower end to the 25 rear end of the frame a of the grain-separator, preferably by plates a a, one applied to the under side of each sill a' of the two frames at their meeting points and bolted in place thereto, thus uniting the stacker and separator.

30 B is the driving-shaft for the stacker, having a pulley b on one end driven by a belt (not shown) in turn driven from the separator. Applied to the bearings B' of this shaft is the folding frame c of an endless belt or belts C, 35 which first receive the straw from the separator and convey or deposit it upon the stacker-belt D. The first or lower section C^X of the belt-bearing frame c is fixed or stationary, the upper section C^{XX} folding against the derrick-frame H, hereinafter referred to.

The stacker-belt frame D' is shown composed of three hinged-together or folding sections D² D³ D⁴; but it may be formed of more or less sections, if desired, and is designed to 45 fold up compactly closely to the belt or apron C when also folded. The stacker apron or belt D consists, preferably, of a series of supplementary endless belts c', connected together by transverse slats or bars, and encompassing rolls or pulleys c² c³ upon two shafts c⁵ c⁶, the upper shaft c⁶ being hung in suitable

boxes c⁷ at the upper ends of the sectional side pieces of the stacker-belt frame D'. Upon the lower shaft c⁶ is supported the lower or bottom section of the stacker-belt frame 55 D', the side bars of said section having applied thereto at their lower ends eyes or boxes d d, through which said shaft passes, but without affecting the said section. This shaft c⁶ is supported or journaled in suitable boxes d' 60 d', secured upon slightly upwardly-extending portions of a turn-table E, giving the stacker a pivotal movement to permit the shifting of the latter, so as to deliver its load or contents in any desired direction, building the stack 65 to the best advantage, or in widening or building outward without requiring movement of the separator. This turn-table is preferably formed in T shape, having its cross-piece E' supported upon oblique bars E², secured upon 70 the frame A, and having its longitudinal arm or portion E³ centrally pivoted by a pivot-bolt c⁷ upon the rear cross-piece or sill E⁴ of the frame A, said longitudinal portion carrying a shaft e, supported in any suitable manner thereon. The longitudinal portion or arm E³ of the turn-table has in its outer end a recess e^X, and from the same at its sides depends pendants h'. A short endless belt f encompasses a roll or pulley e' on the outer end 80 of the shaft e, and a roll or pulley e² upon and driving the lower stacker-belt shaft c⁶. The opposite end of the shaft e also carries a pulley or roll e³, and around this pulley is passed an endless belt g, which also passes around or 85 over two other pulleys h h, journaled in the recess e^X in the outer end of the turn-table E. Said belt g thence passes down under two more pulleys or rolls i i, hung in the pendants h' of the turn-table E, and from there it 90 passes between two series of pulleys or rolls j j, hung upon the under side of the frame A. Passing from these it is carried under two other pulleys or rolls K K, journaled between pendants K' K' of a sill of the frame A. 95 From here the belt is carried up and over a central pulley or roll l upon the driving-shaft B, from which said belt receives its motion and through which primarily the stacker-belt receives motion. This arrangement of or 100 manner of passing the belt g is made necessary by reason of the location of the point

from which the motion is taken, the point of application of the same, and the employment of the turn-table.

For the adjustment or raising and lowering of the stacker D D', I employ a rope or chain F, which is connected to a branch rope or chain f', having its looped ends caught or slipped upon either of two sets of headed pins or projections f² f³ upon the sides of the stacker-belt frame. In an extended position of the stacker-belt frame the branch rope f' is applied to the projections or pins f³; but in its folded position the branch rope is applied to the pins or projections f². The branch rope or chain f' is held with its portions spread apart by the apertured cross-bar f⁴, through whose aperture said rope passes. The rope or chain F passes over a pulley f⁵, swiveled in the under side of the apex of the derrick G, pivotally supported upon the upper cross-bar of an upright stationary frame H, secured upon the horizontal base-frame A. The rope or chain F is wound upon the drum or cylinder of a windlass I, secured upon the top of the grain-separator, and the windlass may be suitably braced in position by a chain or rope h³, connected to a staple or hook h⁴ upon the windlass-frame, and to a ring or staple (not shown) secured farther on to the top of the grain-separator. From this hook or staple h⁴ is also extended a brace chain or rope h², connecting with a bail h⁵, hung upon the derrick G near its apex.

In lieu of the rolls or pulleys e' e² and the belt f, as shown, may be substituted sprocket wheels or pinions and an endless chain, respectively.

Having described this invention, what I claim, and desire to secure by Letters Patent, is—

40

1. The combination, with the supporting or base frame, of the turn-table pivoted thereon, the shifting stacker-belt frame supported upon a shaft upon the turn-table, said shaft being driven by a band from a second shaft 45 upon said turn-table, and an endless band driving said second shaft, and said endless band being driven from the main driving-shaft, the latter band being carried over four or more intermediate series of pulleys or 50 rolls, substantially as shown and described, and for the purpose set forth.

2. The combination, with the supporting or base frame, of the turn-table pivoted thereon, the shifting stacker-belt frame supported 55 upon a shaft upon the turn-table, said shaft being driven by a band from a second shaft upon said turn-table, an endless band driving said second shaft, and said endless band being driven from the main driving-shaft, the latter band being carried over an intermediate series of pulleys or rolls, the folding frame supported upon the base-frame, and the endless belt or apron of said latter folding frame also driven by the main driving-shaft, substantially as set forth.

In testimony whereof I affix my signature in presence of two witnesses.

JOSEPH HOVEY.
